C. BREER

DISHWASHER

Filed July 21, 1920

Inventor:
Carl Breer
by: *W. C. Lind*
His Attorney.

UNITED STATES PATENT OFFICE.

CARL BREER, OF SUMMIT, NEW JERSEY.

DISHWASHER.

Application filed July 21, 1920. Serial No. 397,877.

To all whom it may concern:

Be it known that I, CARL BREER, a citizen of the United States, residing at Summit, in the county of Union and State of New Jersey, have invented new and useful Improvements in Dishwashers, of which the following is a specification.

One of the difficulties in dish washing arises from the shapes of the dishes which make it difficult, if not impossible with most devices, to reach all parts of some dishes without changing the position of the dishes in the apparatus. This is particularly true of cup-shaped dishes and this invention is particularly designed to facilitate the washing of such shaped dishes.

The invention is illustrated in the accompanying drawings as follows:—

Fig. 1 shows a plan view of a dish-washing tray.

Fig. 2 a side elevation of the same.

Fig. 3 an end elevation.

The tray frame is formed with a rectangular upper wire 1 and a lower rectangular shaped wire 2. These are connected by the end wires 3 which are looped at the top forming handles for the tray. Wire netting 4 is drawn across the bottom and formed at the sides, the ends of the wires of the netting being turned over the upper rod completing the tray.

Arranged at intervals in the bottom of the tray are a series of water deflectors 6. These deflectors are formed with the lugs 7 by which they are secured to the wires of the netting. These deflectors preferably are U-bends with inlets 8 opening upwardly and the discharge end 9 opening upwardly. The inlet end and discharge end of the U-bend are preferably slightly above the plane of the netting and have a recess 10 formed between them into which the edge of a cup or similar article may be set, the cup being placed over the discharge end.

These U-bends are distributed with relation to the ordinary size cups or similar articles so that such articles may be placed over the discharge end in an inverted position. Such a cup is shown in dash lines at

11. Cleansing water is directed into the inlet 8 as indicated preferably from a nozzle 12. It will be readily seen that as the water strikes the U-bend when discharged downwardly as indicated in Fig. 3 it is deflected

and discharged into the interior of the inverted cup thoroughly cleansing this cup. The outside of the cup can be readily cleansed by the direct action of the water. Cups may be readily rinsed, if desired, from the spout of an ordinary tea-kettle, the discharge from such spout having ample velocity to be so deflected as to cover the entire interior of the cup. In this way all parts of cup-shaped articles may be thoroughly washed and rinsed without any change in the position of such cups. Ordinarily the bottom of the tray is above any water level so that the full force of a jet may be delivered to the inlet of the deflector.

What I claim as new is:—

1. In a dish-washer, the combination of a dish-support; and a water deflector having an outlet adapted to discharge into a cup-shaped dish on the support and an inlet adapted to receive a jet of water from a different direction than the direction of discharge.

2. In a dish-washer, the combination of a dish-support; and a water deflector having an upwardly directed discharge and an inlet adapted to receive a jet of water from a different direction than the direction of discharge.

3. In a dish-washer, the combination of a dish-support; and a water deflector adapted to discharge water into a dish supported on the dish support, said deflector having an upwardly opening inlet adapted to receive a jet of water.

4. In a dish-washer, the combination of a horizontally extending dish-support; and conduits having U-bends arranged in said support and adapted to discharge into inverted cups arranged over the U-bends and to receive water from above.

5. In a dish-washer, the combination of a horizontally extending dish-support; and conduits having U-bends arranged in said support and having outlets adapted to discharge into inverted cups arranged over the U-bends and inlets adapted to receive water from above, said U-bends each having a recess between the inlet and outlet adapted to receive the edge of the cup.

In testimony whereof I have hereunto set my hand.

CARL BREER.
